CORPORATION; Richard Batt

(57) CLAIM

The ornamental design for a heel support cushion as shown and described.

DESCRIPTION

FIG. 1 is an upper front right side perspective view of a heel support cushion showing our new design;

FIG. 2 is an upper rear left side perspective view of the heel support cushion shown in FIG. 1;

FIG. 3 is a top view of the heel support cushion shown in FIG. 1;

FIG. 4 is a bottom view of the heel support cushion shown in FIG. 1

FIG. 5 is a right view of the heel support cushion shown in FIG. 1;

FIG. 6 is a left view of the heel support cushion shown in FIG. 1;

FIG. 7 is a rear view of the heel support cushion shown in FIG. 1; and,

FIG. 8 is front view of the heel support cushion shown in FIG. 1.

1 Claim, 6 Drawing Sheets
